L. H. CARUFEL

STENCIL

Filed March 21, 1925

Inventor
Louis H. Carufel

By Watson E. Coleman
Attorney

UNITED STATES PATENT OFFICE.

LOUIS H. CARUFEL, OF BISMARCK, NORTH DAKOTA.

STENCIL.

Application filed March 21, 1925. Serial No. 17,286.

To all whom it may concern:

Be it known that I, LOUIS H. CARUFEL, a citizen of the United States, residing at Bismarck, in the county of Burleigh and State of North Dakota, have invented certain new and useful Improvements in Stencils, of which the following is a specification, reference being had to the accompanying drawings.

10 This invention relates to certain improvements in stencils and has relation more particularly to devices of this general character particularly designed and adapted for use in connection with sand dusting screens of the type disclosed in my pending application 15 Serial No. 701,782, filed March 25, 1924, wherein stencils embodying the present invention are disclosed but not claimed, and it is an object of the invention to provide 20 a stencil with a reinforcement to keep the same from spreading when the stencil is subjected to the force of a sand blast.

Another object of the invention is to provide a stencil with a reinforcement embedded 25 in the bottom or cutting portion thereof to maintain the stencil against distortion and to prevent the sand blast disfiguring the object being worked upon or to produce an irregular copy.

30 An additional object of the invention is to provide a stencil having an opening cut therein to produce a desired letter, character or symbol which is further produced by a piece positioned within said opening together with means for maintaining said piece in assembled relation without hindrance or obstruction being offered to the required action of the sand blast.

The invention consists in the details of 40 construction and in the combination and arrangement of the several parts of my improved stencil whereby certain important advantages are attained and the device rendered simpler, less expensive and otherwise more convenient and advantageous for use, as will be hereinafter more fully set forth.

The novel features of my invention will hereinafter be definitely claimed.

50 In order that my invention may be the better understood, I will now proceed to describe the same with reference to the accompanying drawings, wherein:

Figure 1 is a view in plan illustrating a

stencil constructed in accordance with an 55 embodiment of my invention;

Figure 2 is a sectional view taken substantially on the line 2—2 of Figure 1;

Figure 3 is a view in plan of a stencil constructed in accordance with a further 60 embodiment of my invention;

Figure 4 is a sectional view taken substantially on the line 4—4 of Figure 3;

Figure 5 is a view in plan of a stencil constructed in accordance with a still further 65 embodiment of my invention;

Figure 6 is a view in side elevation illustrating the form of my improved stencil before being applied to the work.

As disclosed in the accompanying drawings, 16 denotes a stencil preferably made of rubber and of a type particularly adapted for use in connection with a sand dusting screen as disclosed in my pending application Serial No. 701,782, filed March 24, 1924. 70 Each of the stencils 16 has embedded therein a reinforcement 1 preferably wire strands of requisite gauge extending along the opposite sides of the stencil and set in the bottom or cutting face portion of the stencil or that face portion which engages the object to be cut by the sand blast. The reinforcement 1 serves to hold the stencil from spreading especially when subjected to the force of the sand blast whereby disfiguring of the object or the work is avoided as is also an irregular cutting.

As disclosed in Figure 5, the reinforcement 1^a is continued entirely around the stencil 16^a. The stencil 16^a has a suitable opening *a* cut therein to produce the desired letter, character or symbol, such letter, character or symbol being further produced through the means of a center piece 2 positioned in the opening *a*. This center piece 2 is held in applied position by the tie or bridge pin 3, the portions of said pin disposed across the resultant opening being provided with a covering 19 of rubber so that effective resistance will be offered to the sand blast to prevent cutting of said tie or bridge pin. While Figure 3 shows a stencil to reproduce the letter "O", it is to be understood that a stencil will be similarly constructed in connection with the letters "A", "P" and 100 the like.

It is also to be understood that the tie or bridge portions *b* are raised sufficiently high

from the under surface of the stencil to permit the sand blast to flow therebeneath so that no hinderance or obstruction will be offered to the requisite cutting action of the blast.

The use of the reinforcements 1 and 1^a permit the stencil when it comes out of the mold to be slightly bent and maintained in such formation, as illustrated in Figure 6, 10 so that the stencil when pressed against the work will have close or tight contact with the work.

When the stencil is of a type to comprise one or more tongue portions 4 as disclosed 15 in Figure 5, it is of advantage to provide each of such tongue portions 4 with a reinforcement 5 in order to hold such tongue portion 4 firm to the work while under sand blast pressure.

20 From the foregoing description it is thought to be obvious that a stencil constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. A stencil for a sand blasting screen having an opening, a piece arranged within

said opening, a tie pin disposed through the stencil and the piece, and a rubber coating for the portion of the pin bridging the space 40 between the piece and stencil.

2. A stencil for a sand blasting screen having an opening, a piece arranged within said opening, a tie pin disposed through the stencil and the piece, and a rubber coating 45 for the portion of the pin bridging the space between the piece and stencil, said tie pin being arranged adjacent to the upper surface of the stencil and piece.

3. A stencil for a sand blasting screen 50 having an opening, a piece arranged within said opening, a tie pin disposed through the stencil and the piece, and a coating of sand resisting material for the portion of the pin bridging the space between the piece 55 and stencil.

4. In combination with a rubber stencil for a sand blasting screen, a reinforcement embedded within the stencil and extending 60 along the sides thereof.

5. In combination with a rubber stencil for a sand blasting screen, a reinforcement embedded within the stencil and extending along the sides thereof adjacent the inner 65 face of the stencil.

6. In combination with a rubber stencil for a sand blasting screen, a reinforcement embedded therein and extending around the marginal portions thereof, said reinforcement being positioned adjacent the 70 inner face of the stencil.

In testimony whereof I hereunto affix my signature.

LOUIS H. CARUFEL.
